United States Patent Office

Des. 187,913

Patented May 17, 1960

187,913

SWINGING DOOR

Joseph Lucchino, Los Angeles, Calif.

Application December 22, 1959, Serial No. 58,760

Term of patent 14 years

(Cl. D13—1)

Fig. 2

Fig. 1

I claim:

The ornamental design for a swinging door, as shown.
